United States Patent Office

JEREMY B. WARDWELL, OF GEORGETOWN, DISTRICT OF COLUMBIA.

Letters Patent No. 65,970, dated June 18, 1867.

IMPROVED BEDSTEAD-FASTENING.

The Schedule referred to in these Letters Patent and making part of the same.

TO ALL WHOM IT MAY CONCERN:

Be it known that I, JEREMY B. WARDWELL, of Georgetown, in the county of Washington, and District of Columbia, have invented a new and improved Bedstead-Fastening; and I do hereby declare the following to be a full, clear, and exact description of the same, reference being had to the accompanying drawings, which are made part of this specification, and in which—

Figure 1 is a horizontal section.

Figure 2 is a perspective view.

Similar letters of reference indicate corresponding parts in the two figures.

The dove-tail tenon on the end of the rail is received within a mortise-plate on the post. One side of the mortise rotates to open or close it upon the tenon.

In the drawings, A represents a metallic cap on the end of the rail, being fastened thereon by screws, and having a dove-tail tenon, B, by which the rail is secured in the mortise-plate C of the post. The thickness of the plate is about equal to the length of the neck of the tenon B, and the shoulder or enlargement of the latter rests against the back of the mortise-plate. D is a plate, rotating on a vertical axis in the wings c of the mortise-plate. The plate D is rotated by means of a handle, d, so as when closed to form one side of the mortise, and when opened to permit the dove-tail tenon B to be withdrawn. A recess in the plate A permits the handle d to fold back sufficiently, and when closed the handle lies snugly against the side of the post. This joint is firm and secure, not liable to be jarred loose, and is easily attached to the respective parts of the rail and post.

Having described my invention, what I claim as new, and desire to secure by Letters Patent, is—

The mortise-plate constructed with a rotating side to close upon the neck of the dove-tail tenon of the rail and to open to permit the withdrawal of the tenon, substantially, as described.

JEREMY B. WARDWELL.
